United States Patent Office.

JOSEPH HUBER, OF ST. LOUIS, MISSOURI, ASSIGNOR TO HIMSELF AND
SOLOMON BRUNSWICK, OF SAME PLACE.

Letters Patent No. 102,821, dated May 10, 1870.

CUE-CUTTING MACHINE.

The Schedule referred to in these Letters Patent and making part of the same.

To all whom it may concern:

Be it known that I, JOSEPH HUBER, of St. Louis, in the county of St. Louis and State of Missouri, have made certain new and useful Improvements in Cue-cutting Machines; and I do hereby declare that the following is a full and true description thereof, reference being had to the accompanying drawings and to the letters of reference marked thereon.

This invention has for its object to cut off cue-ends true to the longitudinal axis of a billiard-cue, and smoothly, without leaving serrated edges.

The nature of this invention is in the arrangement of the cue-holder with a head-piece which has the cutter-knife upon it, the head-piece being revolved by the cutter-handle about the holder, whilst, at the same time, the cutter has an independent feed motion, causing it to penetrate into the stuff of the cue.

To enable those herein skilled to make and use my said invention I will now more fully describe the same, referring to the accompanying—

Figure 1 as a side elevation; to

Figure 2 as a plan; and to

Figure 3, as a vertical sectional elevation.

I construct the stock A of proper form to receive in its bore a cue, B.

The inner surface of the stock should be roughened with sand or emery-paper, to grip tightly on the cue and prevent it from rotating.

The stock is arranged to be firmly pressed about the cue by the clamping-ring C, the lower stock being conical and slotted to allow for the clamping movement, as seen in fig. 1.

At the upper end of the stock or holder A is the cap-piece D.

The base d furnishes a rest against which sits the head or tool-piece E. This revolves freely about the vertical part d¹ of the cap D, and is held in place as well as regulated as to speed in movement by the

set-screws e, which engage in the groove d² of said cap D.

The head-piece E, at its upper end, is arranged to fit nicely about the cue so as to confine the same.

Upon its top face the head-piece has the cutter F, pivoted at f and slotted at f¹, so that a radial movement about the pivot f is possible, subject to the control of the set-screw g in the slot f¹.

The cutting-edge f² is thus enabled to move from circumference to the middle of a cue.

The cutter has a handle, f³.

The operation of said parts is as follows:

The cue being properly inserted and clamped, the operator grasps the handle f³, the stock being still held stationary, the head-piece and cutter are turned about the cue end, at the same time the hand-pressure causes the cutting-edge f² to penetrate the stuff of the cue, until the cutter has made the full stroke of its slot, when the cutting-edge will have reached the center of the cue and have made a smooth, true cut.

As before observed, any irregularity of movement of the head-piece E is remedied by adjustment of the screws e.

Having thus fully described my said invention,

What I claim, and desire to secure by Letters Patent, is—

1. The stock A, revolving head E, and cutter F, substantially as and for the purpose set forth.

2. The cutter F, arranged to turn the head-piece E, and at the same time move radially about the pivot f, substantially as set forth.

In testimony of said invention I have hereunto set my hand, in presence of

JOSEPH HUBER.
